[57] CLAIM

The ornamental design for a stand for a hand held optical scanner, as shown and described.

DESCRIPTION

FIG. 1 is a rear view of the stand for a hand held optical scanner of the present invention;

FIG. 2 is a front view of the stand for a hand held optical scanner of the present invention;

FIG. 3 is a right side view of the stand for a hand held optical scanner of the present invention;

FIG. 4 is a left side view of the stand for a hand held optical scanner of the present invention;

FIG. 5 is a top view of the stand for a hand held optical scanner of the present invention;

FIG. 6 is a bottom view of the stand for a hand held optical scanner of the present invention; and,

FIG. 7 is a perspective view of the stand for a hand held optical scanner of the present invention, on a reduced scale, the broken line drawing of a hand held optical scanner is for illustrative purposes only and forms no part of the claimed design.
